His ATTORNEY.

UNITED STATES PATENT OFFICE.

LAWRENCE G. REPELL, OF KANSAS CITY, MISSOURI.

KEY-FASTENER.

No. 889,967.

Specification of Letters Patent.

Patented June 9, 1908.

Application filed August 6, 1907. Serial No. 387,260.

To all whom it may concern:

Be it known that I, LAWRENCE G. REPELL, a citizen of the United States, residing at Kansas City, in the county of Jackson and State of Missouri, have invented certain new and useful Improvements in Key-Fasteners, of which the following is a specification.

My invention relates to improvements in key fasteners.

The object of my invention is to provide a device by means of which a key may be held from being turned to the unlocked position by any one at the outer side of the door.

My invention provides a portable, neat contrivance, which may be readily attached or detached to a door without mutilating the door and with little labor.

20 The novel features of my invention are hereinafter fully described and claimed.

In the accompanying drawings, which illustrate my invention—Figure 1 is an inside elevation of a portion of a door having affixed to it my improved key fastener engaged with the key and in the locked position. Fig. 2 is an elevation taken at right angles to the view shown in Fig. 1. Fig. 3 is a vertical sectional view taken on the dotted line *a*—*b* of Fig. 2. Fig. 4 is a side elevation of the upper end of the key fastener, the shank of the key being shown in cross section. Fig. 5 is a vertical sectional view taken on the dotted line *c*—*d* of Fig. 4. Fig. 6 is a side view of the rotary member detached from its support. Fig. 7 is a horizontal sectional view taken on the dotted line *e*—*f* of Fig. 3. Fig. 8 is a sectional view of the upper part of the key fastener.

40 Similar characters of reference denote similar parts.

1 denotes the door and 2 an ordinary flat shank key. The key fastener is provided with a vertical tubular shank 3 having an open upper end to which is attached at its periphery a ring-like portion 4 which is transversely divided at one side by a radial slot 5 adapted to receive therethrough the shank of the key 2. The ring-like portion 4 is provided with an inner, annular groove 6, in which is rotatively mounted a disk 7, having a radial peripheral notch 8, which, when the rotary disk or member 7 is in the unlocked position shown in Fig. 8, registers with the slot 5 so that the shank of the key 2 may enter said slot and notch. The notch

8 is adapted to fit the key shank and prevent the key from being turned when the key is in the locked position and the rotary member or disk 7 is in the position shown in Figs. 1, 3 and 4, and is held from rotation by the means about to be described.

In the periphery of the rotary member or disk 7, is a recess 9 disposed, when the rotary member is in the locked position shown in Fig. 3, so as to receive the upper end of a bolt 10, vertically slidable at its lower end in a collar 11, rigidly secured in the lower end of the shank 3. Encircling the bolt 10 is a coil spring 12, the lower end of which bears upon the collar 11 and the upper end of which bears against a collar 13, rigidly secured on the bolt 10.

Secured to the lower end of the bolt outside the shank 3 is a thumb piece 14 by means of which the bolt 10 may be retracted against the pressure of the spring 12 from the recess 9 so that the key 2 may be turned, thereby turning the rotary member 7 to a position in which the notch 8 will align with the slot 5, as shown in Fig. 8, thus permitting the fastener to be removed from the key shank.

For releasably securing the key fastener to the door, the following described mechanism is preferably provided:—Pivoted in diametrically opposite transverse openings in the lower end of the shank 3 are the inwardly turned ends of a U-shaped member 15, the opposite transverse portion of which has pivoted to it a U-shaped link 16, which is pivoted to the rectangular eye of a wood screw 17, adapted to be screwed into the door below the escutcheon plate 18 which is fastened on the inner side of the door 1. On one side of the shank 3 is secured a vertical file 19 by means of which, if the key shank is round, the key shank may be flattened on one or both sides so as to enter and fit the notch 8 of the rotary member or disk 7. To limit the opening movement of the member 7 to a position in which the notch 8 will not pass the slot 5, a projection 20 is provided on one side of the member 7 and in a position such that when the rotary member is in the open position shown in Fig. 8 the projection 20 will enter, the recess 21 on one side of the ring-like portion 4 will strike said portion 4.

In employing the invention to fasten a key the screw 17 is first secured in the door, as above described. At this time the slot 5 and notch 8 are in register, as shown in Fig. 8, so that the device may be swung to a position in

which the key shank will enter the slot 5 and radial notch 8. The key 2 is then turned so as to lock the door, and in so turning the key the rotary member or disk 7 is turned to the 5 position shown in Figs. 1, 3, and 4, in which position the bolt 10 will be forced by the spring 12, which serves as an automatic means for performing this function, into the recess 9, thus locking the member 7 against 10 rotation, said member thereby holding the key 2 from turning.

To unlock the door it is only necessary to grasp the finger hold 14 and withdraw the bolt 10 from the recess 9. The rotary member 15 7 will then be free to turn and the key 2 may then be turned so as to unlock the door. When the key 2 is turned so as to unlock the door, if desired, the key may be detached from the key fastener, the parts at this time 20 being in the position shown in Fig. 8, with the notch 8 and slot 5 registering with each other.

Various modifications of my invention may be made within the scope of the appended claims without departing from its spirit.

25 Having thus described my invention, what I claim and desire to secure by Letters Patent is:—

1. In a key fastener, the combination with a support, having a transversely divided, 30 ring-like portion adapted to receive therethrough the key, said ring-like portion having a slot through which the shank of the key may pass, of a member rotatively mounted in said ring-like portion and having a 35 peripheral notch to receive and hold the key shank, said rotary member being rotatable to and from a position in which said notch and slot will register with each other, and releasable means for holding said rotary 40 member in the locked position in which said notch and slot do not register with each other.

2. In a key fastener, the combination with a support having a transverse hole extending 45 therethrough and having a peripheral slot extending from the edges of the support to said hole and adapted to receive therethrough the shank of a key, of a rotary member mounted on said support and having a 50 peripheral notch for receiving and holding

the key against rotation, said notch registering with the said slot when the rotary member is moved to the open position, a locking member movable to and from a position in which it will engage and hold the rotary 55 member in the locked position, and a spring for normally forcing said locking member into engagement with said rotary member.

3. In a key fastener, the combination with a support, having a tubular shank and a 60 ring-like portion having a slot transversely dividing said ring-like portion, of a rotary disk mounted in said ring-like portion and provided with a peripheral notch adapted, when the rotary member is in the open position, to register with said slot, said notch being adapted to receive the key entering said slot and prevent its turning, a bolt 65 slidably mounted in said tubular shank and provided with means for engaging and holding said rotary member when said rotary member is in the locked position, and a spring located in said shank and normally forcing said bolt into a position in which the bolt 70 will engage said rotary disk.

4. In a key fastener, the combination with a support having a tubular shank and a ring-like portion having a slot transversely dividing said ring-like portion, of a rotary disk mounted in said ring-like portion and provided 80 with a peripheral notch for receiving a key to prevent its turning, said notch registering with said slot when the rotary member is in the open position, said rotary member having a recess, a bolt 85 slidable in and out of said recess when the rotary member is in the locked position, said bolt being mounted in said shank and having means by which it may be withdrawn from said recess, a spring for forcing said bolt into said recess, and 90 means for securing said support to a door or other object.

In testimony whereof I have signed my name to this specification in presence of two subscribing witnesses.

LAWRENCE G. REPELL.
